(57) **CLAIM**

The ornamental design for the paintbrush having wave-shaped bristles, as shown and described.

DESCRIPTION

FIG. 1 is a top plan view of a paintbrush having wave-shaped bristles showing my new design,

FIG. 2 is a front elevational view thereof, the broken lines showing a ferrule and a handle being for illustrative purposes only and forming no part of the claimed design; and, FIG. 3 is a right side view of FIG. 2, of which the left side view is a mirror image.
